UNITED STATES PATENT OFFICE.

GEORGE H. PIERCE, OF MELROSE, MASSACHUSETTS.

PRINTING-PRESS.

No. 879,897.

Specification of Letters Patent.

Patented Feb. 25, 1908.

Application filed April 2, 1907. Serial No. 365,950.

To all whom it may concern:

Be it known that I, GEORGE H. PIERCE, a citizen of the United States, residing at Melrose, in the county of Middlesex and State 5 of Massachusetts, have invented new and useful Improvements in Printing-Presses, of which the following is a specification.

This invention relates to improvements in printing presses, and the object is to provide a printing press particularly adapted for use in the printing and especially the numbering of tickets, tags, and the like so constructed and arranged as to be easily and quickly adjusted for a wide range of differing 15 conditions and at the same time simple, accessible, and compact and capable of being operated at a high rate of speed.

Other objects and advantages will appear hereafter.

20 The invention consists in the combination and arrangement of parts set forth in the following specification and particularly pointed out in the claims thereof.

Referring to the drawings: Figure 1 is a 25 side elevation of my improved printing press, partly broken away. Fig. 2 is a side elevation of the same viewed from the opposite direction from Fig. 1. Fig. 3 is an elevation, partly broken away and partly in section, 30 viewed from the left of Fig. 1. Fig. 4 is a section, partly in elevation, taken on line 4—4 of Fig. 3, looking toward the left. Fig. 5 is a section, partly in elevation, taken on line 5—5 of Fig. 1, looking toward the right. 35 Fig. 6 is a detail side elevation of a slide and a pawl mounted thereon, the same forming a portion of the mechanism for reciprocating the ink distribution-roll. Fig. 7 is a plan section taken on line 7—7 of Fig. 6. Fig. 8 is 40 a section, partly in elevation, taken on line 8—8 of Fig. 2, looking toward the left. Fig. 9 is a detail plan, partly in section, taken on line 9—9 of Fig. 3. Fig. 10 is an elevation of the form-carrier, viewed from the left of 45 Figs. 1 and 4. Fig. 11 is an enlarged detail side elevation of one of the wedges used to retain in place on the form-carrier the slotted plate on which the numbering devices are mounted, said figure showing also the screw 50 for adjusting said wedge. Fig. 12 is an enlarged detail elevation of one of the numbering machines. Fig. 13 is a sectional elevation taken on line 13—13 of Fig. 12, looking toward the left.

55 Like numerals refer to like parts throughout the several views of the drawings.

In the drawings, 15 is a bed having a shaft 16 journaled thereon and extending longitudinally thereof. A frame 17 is slidably mounted on the bed 15 and may be moved longitudinally thereof and when placed in the desired position may be clamped thereto by means of a clamping plate 18, a screw 19 fast to said frame, and a nut 20 having screw-threaded engagement with said screw. A 60 miter gear 21 is non-rotatably mounted on the shaft 16, said gear being provided with a hub 22 journaled in a bearing 23 formed on the frame 17. A key 24 fast to the gear 21 is adapted to slide in a key-way 25 formed in the shaft 16. A miter gear 26 is fast to a 65 spur gear 27, said miter gear and said spur gear being rotatably mounted on a stud 28 fast to the frame 17.

The miter gear 21 meshes into the miter 75 gear 26. The spur gear 27 meshes into a spur gear 29 fast to a shaft 30, said shaft being journaled in bearings 31, 31 formed in the frame 17. A crank-disk 32 is fast to the shaft 30. The spur gear 29 which constitute 80 also a crank-disk is provided with a crank-pin 33, and the crank-disk 32 is provided with a corresponding crank pin 34. A form-carrier 35 slidably mounted on the frame 17 has fast thereto at opposite sides, respectively, two studs 36 and 37. The stud 36 is connected to the crank-pin 34 by a connecting rod 38 and the stud 37 is connected to the crank-pin 33 by a corresponding connecting rod 39. A plate 40 provided with a slot 41 85 extending transversely of the bed 15 is detachably attached to the form-carrier 35 by means of two wedges 42, 42 which are adjusted by means of screws 43, 43, said screws having screw-threaded engagement with the 90 form-carrier 35. Each of the wedges 42 is provided, respectively, with a slot 44 in which its corresponding screw 43 is located. Each of the screws 43 is provided, respectively, with a flange 45 adapted to prevent 95 movement of the wedge 42 longitudinally of said screw. When it is desired to remove the plate 40, the screws 43, 43 are rotated in the proper direction to withdraw the wedges 42, 42 slightly, thereby releasing the plate 100 40 and permitting said plate to be withdrawn from the form-carrier 35. A plurality of numbering machines 46, are adjustably mounted on the plate 40. Each of the numbering machines 46 comprises in its construction a type-wheel holder 47 having a 105 tubular shank 48 located in the slot 41. The

shanks 48 may be entirely cylindrical throughout, as shown in Fig. 4, or if desired one or more of said shanks may be provided with a squared portion 49, as shown in Fig. 5 12, adapted to engage the slot 41 and normally prevent the type-wheel holder 47 from being rotated on the axis of its shank 48. I prefer to have part of the holders 47 provided with a squared portion 49 and part without. 10 Each of the numbering machines 46 is provided, respectively, with a nut 50 having screw-threaded engagement with the shank 48.

In the case of the shank 48 provided with a 15 squared portion 49, the nut 50 may be rotated in the proper direction to permit said squared portion to be disengaged from the slot 41, thereby permitting the holder 47 to be rotated on the axis of its shank 48. When 20 placed in its proper position, the holder 47 may be clamped to the plate 40 by rotating the nut 50 in the proper direction, it being understood that the squared portion 49 makes it unnecessary to carefully adjust the 25 holder 47 as regards the rotary adjustment of said holder. In the case of the shank 48 being cylindrical as shown in Fig. 4, the nut 50 may be loosened and the holder 47 may then be rotated on the axis of its shank 48 30 until said holder bears any desired angular relation to the plate 40.

It will be understood that the numbering devices 46 besides being capable of the adjustments hereinbefore described, may also 35 be adjusted longitudinally of the slot 41. It will be understood that the plate 40 together with the numbering machines 46 thereon may be easily and quickly removed from the form-carrier 35 by loosening the screws 43, 43 40 hereinbefore described. Each of the numbering machines 46 is provided, respectively, with a plunger 51 slidably mounted within the shank 48. A compression spring 52 bears at its upper end against a plug 53 and at its 45 lower end against a pin 54, said pin being located in slots 55, 55 formed in the plunger 51, said slots and said pin being adapted to limit the movement of the plunger 51. Two links 56, 56 are pivotally connected at their 50 upper ends to a pin 57 which passes through the plunger 51, said links being pivotally connected at their lower ends to two oscillatory pawl carriers 145, 145 by a pin 146, there being a multiple pawl 58 interposed between 55 said pawl carriers and pivotally mounted on said pin. A plurality of rotary type wheels 59 are mounted in the type wheel holder 47 and are adapted to be rotated by a multiple pawl 58 in a well known manner to print consecutive 60 numbers the features of the pawl 58 and type wheels 59 being patented and I do not claim any of said features. A plurality of rotary type-wheels 59 are rotatably mounted in the type-wheel holder 47.

65 A plate 60 forming a part of the frame 17 is

provided with a slot 61 corresponding to the slot 41 of the plate 40. A plurality of stop-screws 62 are located in the slot 61 and may be adjusted longitudinally thereof by loosening the nuts 63. The stop-screws 62 may 70 also be adjusted toward and away from the plungers 51. As the form-carrier 35 is reciprocated by the mechanism hereinbefore described operatively connected therewith, the plungers 51 during each upward movement of said form-carrier strike the stop-screws 62, thereby causing the holders 47 to be moved upwardly with relation to the plungers 51, consequently rotating the type wheels 59. On the next downward movement of the form carrier 35, the springs 52 return the plungers 51, the links 56, and the pawl 58 to their normal or starting position. A platen 64 secured to the frame 17 is provided with a suitable pad 65 held thereon by 85 means of a clamp 66. Two guides 67, 67 are mounted on a rod 68, said rod being mounted on the frame 17.

The guides 67, 67 are adapted to guide a strip of paper 69 across the upper side of the 90 pad 65, said strip of paper having an intermittent feed movement imparted thereto by any suitable means, not shown. An ink-fountain 70 is mounted on the frame 17, and a fountain-roll 71 is fast to a shaft 72, said fountain-roll being adapted to receive a film of ink thereon from the fountain 70 in a well known manner. The shaft 72 is journaled in suitable bearings formed in the frame 17. An ink-distribution-roll 73 is fast to a shaft 95 74, said shaft being journaled in suitable bearings in the frame 17. A ductor-roll 75 preferably formed of soft composition is fast to a shaft 76, said shaft being rotatably mounted at its opposite ends in two arms 10 77, 77, said arms being pivotally mounted at 78, 78 on the frame 17. Springs 79, 79 are adapted to hold the ductor-roll 75 normally in contact with the ink-distribution roll 73.

Two pins 80, 80 mounted on the arms 11 77, 77 extend toward the form-carrier 35. A spring 81 preferably formed of cylindrical wire is secured at its central portion to the form-carrier 35, the opposite ends of said spring being adapted to engage the pins 80, 11 80 and thereby move the ductor-roll 75 into contact with the fountain-roll with each upward movement of said form-carrier. The spring 81 is adapted to yield and permit the form-carrier 35 to continue its upward 11 movement after the ductor-roll 75 has come into contact with the fountain-roll 71, thereby causing said ductor-roll to "dwell" upon the fountain-roll 71 a short period of time during which time said fountain-roll is rotated as hereinafter described.

As the form-carrier 35 is reciprocated, the ductor-roll 75 is adapted to contact alternately with the fountain-roll 71 and the ink-distribution roll 73, thereby taking a supply 11

of ink from said fountain-roll and transferring it to said ink-distribution roll. A shaft 82 journaled in suitable bearings in the frame 17 has a spur gear 83 fast thereto, said spur gear meshing into the spur gear 29. A crank-disk 84 is fast to the shaft 82 at the end of said shaft which is opposite to the end to which the gear 83 is fast. The crank-disk 84 is provided with a crank-pin 85 extending 10 therefrom. A ratchet 86 is fast to the shaft 72, while a pawl-carrier 87 is rotatably mounted on said shaft. A pawl 88 pivotally mounted on the pawl-carrier 87 is held in contact with the ratchet 86 by means of a spring 89 fast at one end to said pawl and at the other end to said pawl-carrier. A block 90 is pivotally mounted on the pawl-carrier 87. A link 91 pivotally connected at its lower end to the crank-pin 85 is slidably 15 mounted in the block 90 and has two collars 92 and 93 adjustably mounted thereon, said collars being adapted to alternately strike the block 90 and thereby rock the pawl-carrier 87 on the shaft 72 thus imparting to the 20 ratchet 86, the shaft 72, and the fountain-roll 71 an intermittent rotary movement.

The collars 92 and 93 may be adjusted on the link 91 to vary the amount of feed of the fountain roll 71 for each rotation of the shaft 30 82. A sprocket-wheel 94 fast to the shaft 82 is operatively connected to a second sprocket-wheel 95 by means of a chain 96. The sprocket-wheel 95 is fast to a spur gear 97, said sprocket-wheel and said gear being rotatably mounted on a stationary stud 98 fast to the frame 17. The gear 97 meshes into a pinion 99 fast to the shaft 74, said pinion being of substantially double the width or face of the gear 97. A collar 100 35 provided with an annular groove 101 is also fast to the shaft 74. A crank-disk 102 is provided with a crank-pin 103 located in the annular groove 101. The crank-disk 102 is fast to a shaft 104 journaled in a bracket 105, said shaft having fast thereto at its upper 40 end a ratchet 106. A slide 107 is slidably mounted on the frame 17, said slide having pivoted thereon a pawl 108, said pawl being held in operative engagement with the ratchet 106 by means of a spring 109. The 45 slide 107 is provided with a slot 110 in which is located the squared portion 111 of the stud 37.

As the form-carrier 35 moves up and 50 down, the squared portion 111 of the stud 37 plays in the slot 110, thereby imparting to the slide 107 a horizontal reciprocatory movement, thereby causing the pawl 108 to impart to the ratchet 106 an intermittent rotary movement. The crank-pin 103, therefore, imparts to the shaft 74 and the ink-distribution roll 73 fast thereto a slow reciprocatory movement, the pinion 99 sliding with relation to the gear 97. A shaft 112 55 journaled in suitable bearings in the frame 17

has fast thereto a sprocket-wheel 113, said sprocket-wheel being operatively connected to a sprocket-wheel 114 by means of a chain 115, the tension of which may be adjusted by means of an idler sprocket-wheel 116. 70

The sprocket-wheel 114 is fast to the shaft 82. Two sprocket-wheels 119 and 120 are journaled on studs 121 and 122, respectively, said studs being adjustably mounted on brackets 123 and 124, respectively. Two 75 sprocket-wheels 125 and 126 are rotatably mounted on studs 127 and 128, respectively, said studs being adjustably mounted on brackets 129 and 130, respectively. Two sprocket-wheels 131 and 132 are rotatably 80 mounted on the frame 17. A chain 133 passes partway around the sprocket-wheel 117, partway around the sprocket-wheel 125, partway around the sprocket-wheel 131, and partway around the sprocket-wheel 119. 85 In like manner a chain 134 passes partway around the sprocket-wheel 118, partway around the sprocket-wheel 120, partway around the sprocket-wheel 132, and partway around the sprocket-wheel 126. 90

The chains 133 and 134 are moved in unison in the direction of the arrows *a* (Figs. 1, 2 and 4) whereas the shaft 74 and the ink-distribution roll 73 which is fast to said shaft rotate in the direction of the arrows *b* 95 (Figs. 1, 2, and 4). In other words, the periphery of the ink-distribution roll 73 moves in a direction opposite to that of the chains 133 and 134. Two ink-carrier rolls 135 and 136 are rotatably mounted on the chains 133 and 134 and are placed equidistantly on said chains. Each of the ink-carrier rolls 135 and 136 is adapted to alternately contact with the ink-distribution roll 73 and the faces of the type-wheels 59, 100 105 it being understood that while each of said ink-carrier rolls is passing partway around said ink-distribution roll that said ink-distribution roll is rotated so rapidly as to deposit a large amount of its film of ink onto 110 the ink-carrier roll 135 or the ink-carrier roll 136 as the case may be.

Two wheels 137 and 138 are journaled on the ink-carrier roll 136 and similarly two wheels 139 and 140 are journaled on the ink-carrier roll 135. The wheels 137 and 139 are adapted to roll on a track 141, said track being mounted on the frame 17 and being adjustable vertically, there being screws 143 having screw-threaded engagement with the 115 frame 17, said screws being adapted to clamp the track 141 to said frame 17. Similarly the wheels 138 and 140 are adapted to roll on a track 142, said track being mounted on the frame 17 and being adjustable vertically, there being two screws 144, 144 having screw-threaded engagement with the frame 17 and extending through vertical slots formed in said track, said screws being adapted to clamp said track to said frame. 130

By adjusting the tracks 141 and 142 the ink-carrier rolls 135 and 136 may be caused to bear with more or less pressure against the type faces of the type-wheels 59 as said rolls are moved thereacross. By having two ink-carrier rolls 135 and 136 it is possible to run the chain 133 and 134 at half the speed as if only one ink-carrier roll were used.

The general operation of the machine hereinbefore specifically described is as follows: The strip of paper 69 is fed intermittently across the upper side of the pad 65 and when said strip is held stationary the form-carrier 35 descends, thereby bringing the type-wheels 59 into contact with said strip of paper. The type-wheels, 59 with each reciprocation of the form-carrier 35, receive a fresh supply of ink from the ink-carrier rolls 135 and 136 alternately, said ink-carrier rolls receiving their supply of ink from the ink-distribution roll 73, said ink-distribution roll receiving its supply of ink from the ductor-roll 75 and said ductor-roll receiving its supply of ink from the fountain-roll 71 as hereinbefore described. As the form-carrier 35 is raised, the plungers 51 strike the stop-screws 62 and said plungers actuate the type-wheels 59, thus causing the numbering machines 46 to print on the strip of paper 69 consecutive numberings.

It will be evident that by placing on the bed 15 a second printing head identical with the one hereinbefore described the numbering machines of both of said printing heads may be so arranged that in conjunction with each other they may be caused to print on the strip of paper 69 a continuous row of numerals extending transversely of said strip of paper. It will also be evident that the frame 17 may be easily and quickly adjusted longitudinally of the bed 15, this feature being of great value where there are a number of printing heads and cutting and punching heads mounted on the bed.

Having thus described my invention what I claim and desire by Letters Patent to secure is:

1. In a printing press, a frame, a form-carrier slidably mounted on said frame, a stop supported on said frame, mechanism to impart a reciprocatory movement to said form-carrier, a type-wheel holder supported on said form-carrier and rotatably adjustable thereon, a type-wheel rotatably mounted in said holder, a plunger slidably mounted in said holder adapted to strike said stop plunger operatively connected to said type-wheel, and an ink-carrier roll movable across said type-wheel.

2. In a printing press a frame, a form-carrier slidably mounted on said frame, mechanism to impart a reciprocatory movement to said form-carrier, a type-wheel holder supported on said form-carrier and rotatably adjustable thereon, a type-wheel rotatably mounted in

mounted in said holder, a stop adjustably mounted on said frame, a plunger slidably mounted in said holder adapted to strike said stop, said plunger operatively connected to said type wheel, and an ink-carrier roll movable across said type-wheel.

3. In a printing press, a frame, a form-carrier slidably mounted on said frame, a stop supported on said frame, mechanism to impart a reciprocatory movement to said form-carrier, a type-wheel holder supported on said form-carrier and rotatably adjustable thereon, a type-wheel rotatably mounted in said holder, a plunger slidably mounted in said holder adapted to strike said stop, said plunger operatively connected to said type-wheel, an endless chain carried by said form-carrier, an ink carrier roll journaled on said endless chain, and gearing operatively connected to said chain.

4. In a printing press, a frame, a form-carrier slidably mounted on said frame, a stop supported on said frame, mechanism to impart a reciprocatory movement to said form-carrier, a type-wheel holder supported on said form-carrier and rotatably adjustable thereon, a type-wheel rotatably mounted in said holder, a plunger slidably mounted in said holder adapted to strike said stop, said plunger operatively connected to said type-wheel, two endless chains carried by said form-carrier, an ink-carrier roll journaled on said endless chains, and gearing operatively connected to said chains.

5. In a printing press, a frame, a form-carrier slidably mounted on said frame, a stop supported on said frame, mechanism to impart a reciprocatory movement to said form-carrier, a type-wheel holder supported on said form-carrier and rotatably adjustable thereon, a type-wheel rotatably mounted in said holder, a plunger slidably mounted in said holder adapted to strike said stop, said plunger operatively connected to said type-wheel, two endless chains carried by said form-carrier, an ink-carrier roll journaled on said endless chains, gearing operatively connected to said chains, two wheels journaled on opposite ends, respectively, of said roll, and two tracks located on opposite sides, respectively, of said frame, said wheels adapted to roll on said tracks, respectively.

6. In a printing press, a frame, a form-carrier slidably mounted on said frame, a stop supported on said frame, mechanism to impart a reciprocatory movement to said form-carrier, a type-wheel holder supported on said form-carrier and rotatably adjustable thereon, a type-wheel rotatably mounted in said holder, a plunger slidably mounted in said holder adapted to strike said stop, said plunger operatively connected to said type-wheel, two endless chains carried by said form-carrier, an ink-carrier roll journaled on said endless chains, gearing operatively con-

- 5 nected to said chains, two wheels journaled on opposite ends, respectively, of said roll, and two tracks located on opposite sides, respectively, of said frame, said wheels adapted to roll on said tracks, respectively, said tracks being adjustable toward and away from said chains.
7. In a printing press, a frame, a stop supported on said frame, a movable form-carrier, a type-wheel holder mounted on said form-carrier and rotatably adjustable thereon, a plurality of type-wheels rotatably mounted in said holder, a plunger slidably mounted in said holder adapted to strike said stop, said plunger operatively connected to said type-wheels, and an ink-carrier roll movable across said type-wheels.
- 10 8. In a printing press, a frame, a form-carrier movably mounted on said frame, a stop supported on said frame, a type-wheel holder rotatably adjustable on said form-carrier, a plurality of type-wheels rotatably mounted on said holder, a plunger slidably mounted in said holder, said plunger adapted to strike said stop, said plunger operatively connected to said type-wheels, and an ink-carrier roll movable across said type-wheels.
- 15 9. In a printing press, a frame, a stop supported on said frame, a movable form-carrier, a type-wheel holder mounted on said form-carrier and rotatably adjustable thereon and transversely thereof, a plurality of type-wheels rotatably mounted in said holder, a plunger slidably mounted in said holder, said plunger adapted to strike said stop, said plunger operatively connected to said type-wheels, and an ink-carrier roll movable across said type-wheels.
- 20 10. In a printing press, a frame, a stop supported on said frame, a reciprocatory form-carrier, a type-wheel holder mounted on said form-carrier and rotatably adjustable thereon and transversely thereof, a plurality of type-wheels rotatably mounted in said holder, a plunger slidably mounted in said holder, said plunger adapted to strike said stop, said plunger operatively connected to said type-wheels, and an ink-carrier roll movable across said type-wheels.
- 25 11. In a printing press, a frame, a stop supported on said frame, a movable form-carrier, a plate detachably attached to said form-carrier, a type-wheel holder adjustably mounted on said plate, a plurality of type-wheels rotatably mounted in said holder, a plunger slidably mounted in said holder, said plunger adapted to strike said stop, said plunger operatively connected to said type-wheels, and an ink-carrier roll movable across said type-wheels.
- 30 12. In a printing press, a frame, a stop supported on said frame, a movable form-carrier, a plate detachably attached to said form-carrier, a type-wheel holder located in said slot and adjustable therein, a plurality of type-wheels rotatably mounted in said holder, a plunger slidably mounted in said holder, said plunger adapted to strike said stop, said plunger operatively connected to said type-wheels, and an ink-carrier roll movable across said type-wheels.
- 35 13. In a printing press, a frame, a stop supported on said frame, a reciprocatory form-carrier, a plate detachably attached to said form-carrier, said plate provided with a slot extending transversely of said form-carrier, a type-wheel holder located in said slot and adjustable therein, a plurality of type-wheels rotatably mounted in said holder, a plunger slidably mounted in said holder, said plunger adapted to strike said stop, said plunger operatively connected to said type-wheels, and an ink-carrier roll movable across said type-wheels.
- 40 14. In a printing press, a frame, a plurality of stops supported on said frame, a movable form-carrier, a plate detachably attached to said form-carrier, said plate provided with a slot, a plurality of type-wheel holders located in said slot and adjustable therein, a series of type-wheels rotatably mounted in each of said holders, a plurality of plungers slidably mounted in said holders, respectively, said plungers adapted to strike said stops, said plungers being operatively connected to said series of type wheels, respectively, and an ink-carrier roll movable across said type-wheels.
- 45 15. In a printing press, a frame, a stop supported on said frame, a platen, a form-carrier movable toward and away from said platen, a type wheel holder provided with a hollow shank fast to said form-carrier, a type wheel rotatably mounted on said holder, and a plunger located within said shank adapted to strike said stop, said plunger being operatively connected to said type wheel.
- 50 16. In a printing press, a frame, a stop supported on said frame, a platen, a form-carrier movable toward and away from said platen, a type wheel holder provided with a hollow shank rotatably mounted on said form-carrier, a type wheel rotatably mounted on said holder, and a plunger located within said shank adapted to strike said stop, said plunger being operatively connected to said type wheel.
- 55 17. In a printing press, a frame, a stop adjustable transversely of said frame, a platen, a form-carrier movable toward and away from said platen, a type wheel holder provided with a hollow shank fast to said form-carrier and adjustable transversely thereof, a type wheel rotatably mounted on said holder, and a plunger located within said shank adapted to strike said stop, said plunger being operatively connected to said type wheel.
- 60 18. In a printing press, a frame, a stop supported on said frame, a movable form-carrier, a plate detachably attached to said form-carrier, said plate provided with a slot extending transversely of said form-carrier,

18. In a printing press, a frame, a stop supported on said frame, a platen, a form-carrier movable toward and away from said platen, a type wheel holder provided with 5 a hollow shank fast to said form-carrier, a type wheel rotatably mounted on said holder, and a plunger located within said shank adapted to strike said stop, said plunger being operatively connected to said type wheel, said 10 stop being adjustable toward and away from said plunger.

19. In a printing press, a frame, a stop supported on said frame, a platen, a form-carrier movable toward and away from said 15 platen, a type wheel holder provided with a hollow shank fast to said form-carrier, a type wheel rotatably mounted on said holder, a plunger located within said shank adapted to strike said stop, a pawl adapted to rotate 20 said type wheel, and a link connecting said pawl to said plunger.

20. In a printing press, a frame, a stop supported on said frame, a platen, a form-carrier movable toward and away from said 25 platen, a type wheel holder provided with a hollow shank fast to said form-carrier, a type wheel rotatably mounted on said holder, a plunger located within said shank adapted to strike said stop, a pawl adapted to rotate 30 said type wheel, a pair of oscillatory pawl carriers on which said pawl is mounted, and a pair of links connecting said pawl carriers to said plunger.

21. In a printing press, a frame, a stop supported on said frame, a platen, a form-carrier movable toward and away from said 35 platen, a plate supported on said form-carrier, a type wheel holder provided with a hollow shank extending through said plate, 40 a nut having screw-threaded engagement with said shank adapted to clamp said holder to said plate, a type wheel rotatably mounted on said holder, and a plunger located within said shank adapted to strike 45 said stop, said plunger being operatively connected to said type wheel.

22. In a printing press, a frame, a stop supported on said frame, a platen, a form-carrier movable toward and away from said platen, a plate supported on said form-carrier, said plate provided with a slot, a type wheel holder provided with a hollow shank extending through said slot, a nut having screw-threaded engagement with said shank adapted to clamp said holder to said plate, a type wheel rotatably mounted on said holder, and a plunger located within said shank adapted to strike said stop, said plunger being operatively connected to said type wheel. 50 55

23. In a printing press, a frame, a stop supported on said frame, a platen, a form-carrier movable toward and away from said platen, a type wheel holder provided with a hollow shank fast to said form-carrier, a type wheel rotatably mounted on said holder, a plunger located within said shank adapted to strike said stop, said plunger being operatively connected to said type wheel, and a spring adapted to move said plunger toward said stop. 60 65 70

24. In a printing press, a frame, a stop supported on said frame, a platen, a form-carrier movable toward and away from said platen, a type-wheel holder provided with a hollow shank fast to said form-carrier, a type wheel rotatably mounted on said holder, a hollow plunger located within said shank adapted to strike said stop, a pawl adapted to rotate said type wheel, a pair of oscillatory pawl carriers on which said pawl is mounted, a pair of links connecting said pawl carriers to said plunger, and a spring located in said plunger, one end of said spring bearing against said holder and the other against said plunger. 75 80 85

In testimony whereof I have hereunto set my hand in presence of two subscribing witnesses.

GEORGE H. PIERCE.
